BOOT OR SHOE

Oakley Hutchison, Pedro, Ohio

Application December 9, 1936, Serial No. 115,036

2 Claims. (Cl. 36—45)

The present invention relates to improvements in boots and shoes.

Heretofore when overshoes were worn with boots or shoes difficulties were experienced in keeping the overshoe on the boot or shoe. Such overshoes also permitted mud, snow, slush and water to pass between the boot and overshoe, destroying the effectiveness of the overshoe and causing discomfort to the wearer.

10 An important object of the present invention is the provision of an article of footwear such as a boot or shoe which when worn with an overshoe will prevent the entrance of water, dirt, mud or snow into the overshoe.

15 Another object of the invention is to provide a boot or shoe which when worn with an overshoe will prevent accidental dislodgement of the overshoe.

20 A further object of the invention is the provision of a boot or shoe which is of attractive appearance when worn with or without an overshoe, and which when worn with an overshoe will give the overshoe the appearance of being an integral part of the boot or shoe.

25 Other objects and advantages of the invention will be apparent during the course of the following description.

In the accompanying drawing, which forms a part of this specification and wherein like characters of reference denote like parts throughout:

Figure 1 is a perspective view of a boot or high-topped shoe embodying the invention, and showing an overshoe in place thereon.

35 Figure 2 is a transverse vertical sectional view of the boot or shoe looking towards the rear thereof.

Figure 3 is a similar view of the boot or shoe without the overshoe.

40 Figure 4 is a perspective view of a shoe embodying the present invention, the overshoe being indicated in dotted lines, and,

Figure 5 is a transverse vertical sectional view thereof looking towards the heel portion of 45 the shoe.

In the drawing, wherein for the purpose of illustration is shown a preferred embodiment of the invention, the numeral 10 designates the sole of a boot or shoe having a heel 11 and an upper 12. In Figures 1 to 3 the boot is illustrated as the high-topped shoe variety having a top or leg portion 13 divided in front for its entire length and having eyelets or the like along the divided edges for the reception of suitable laces

55 14. In this type of footwear suitable straps 15

are usually disposed near the top of the shoe for further securing the divided portions together, as seen in Figure 1.

An important feature of the present invention is the formation of the sole 10 and upper 12 5 separately from the leg or top portion 13. When the parts are assembled, the upper 12 extends up into the top portion 13 and is secured thereto by a row of stitching 16 or other securing means at a point spaced a substantial distance 10 from the lower edge of the top portion 13. The lower portion of top 13 extends below the row of 15 stitches 16 to form a flap 17 which normally hugs the upper 12 and conforms to the shape thereof. The flap 17 extends completely around 15 the upper 12 terminating at the divided forward portion of the leg portion 13, its upper limit being defined by the row of stitches 16 which preferably curves upwardly at front and rear to conform generally to the shape of the open 20 top of the usual overshoe. The laces 14 and eyelets preferably extend down to a point adjacent the bottom of the flap so that tightening of the laces serves to draw the flap into close contact with the boot or shoe.

25 A strap 18 of leather or other suitable flexible material is secured at one end to the lower portion of flap 17 and is adapted to extend below the arch of the boot or shoe and engage a suitable buckle 19 secured to the other side of 30 the flap 17. The strap 18 and the buckle holding tab may be formed integrally with the flap 17 or secured thereto by stitching or other suitable means.

When the boot or shoe is to be worn without 35 overshoes, the strap 18 is passed under the arch of the shoe adjacent the heel 11 and tightly held by the buckle to hold the flap 17 in place, as seen in Figure 3. When overshoes are to be worn, the strap 18 is unbuckled and laces 14 40 loosened before the overshoe 20 is placed on the shoe. The flap 17 may then be folded up away from the shoe to permit the overshoe taking its place under the flap, or the flap may be loosened sufficiently to permit the overshoe to 45 extend up inside of the flap. The laces 14 are then tightened and strap 18 passed about the overshoe and secured in position by the buckle, to securely hold the overshoe in position on the boot or shoe as seen in Figures 1 and 2.

50 The flap 17 fits snugly about the overshoe, preventing the entrance of water, mud, snow or the like into the top of the overshoe and the flap and strap prevent accidental removal of the overshoe. This is particularly important in 55

boots or hightopped shoes used for work or in the country as there is a tendency in mud or slush for the overshoe to be pulled from the boot or shoe by suction or by contact with some object or the crust which forms on the top of snow. When the overshoe is secured in place by the flap 17 and strap 18 it becomes for all practical purposes an integral part of the boot or shoes.

10 In Figures 4 and 5 the invention is shown applied to a street shoe having the sole 10', heel 11' and upper 12'. The top portion 13' of the upper is formed separately from the lower portion 12' thereof and is stitched thereto to form 15 the flap 17' provided with strap 18' and buckle 19'. The flap 17' may have any suitable ornamental contour and extends over the overshoe 20' to seal the top thereof and to hold the overshoe in place. The overshoe may also have an 20 ornamental appearance and may be so designed as to give the appearance of being an integral part of the shoe.

If desired the strap and buckle may be dispensed with and the tension placed on the flap 25 17' by laces 14' relied upon for securing the overshoe in position. However, for positive retention of the overshoe, the use of strap 18' and buckle 19' is preferred.

It will be seen that I have provided a boot or 30 shoe which has an attractive appearance when worn with or without an overshoe, and which when worn with an overshoe will seal the overshoe against the ingress of foreign matter while securing the overshoe in place against accidental 35 removal.

While it is preferred to form the flaps 17 and 17' by overlapping the top portion of the footwear over the lower portion of the upper, the flap may obviously be formed in some other manner.

40 While I have shown and described the preferred embodiment of my invention it is to be understood that various changes in the size, shape and arrangement of the parts may be made without departing from the spirit of my invention or the scope of the subjoined claims.

Having thus described my invention, what I claim and desire to protect by Letters Patent is:

1. An article of footwear for outdoor use comprising a substantially rigid sole and heel, a substantially flexible upper secured to the sole, a leg portion of flexible material secured to the upper at a point spaced above the lower end of the leg portion to form a depending flap on the exterior of the upper, said flap being adapted to extend over an overshoe, a buckle secured to the flap on one side of the upper, and a strap secured to the flap on the other side of the upper and adapted to extend beneath the arch portion of the sole to adjustably engage the buckle, whereby the strap will hold the flap in position when the footwear is worn without an overshoe and hold the flap and overshoe in position when an overshoe is worn on the footwear, said article of footwear having the appearance of the usual high top footwear when worn without the overshoe. 20

2. An article of footwear for outdoor use comprising a substantially rigid sole and heel, a substantially flexible upper secured to the sole, a leg portion of flexible material permanently secured to the upper at a point spaced above the lower end of the leg portion to form a depending flap on the exterior of the upper, said flap being adapted to extend over an overshoe worn on the footwear, the upper being unbroken and the leg portion being divided by a slit extending to a point adjacent said flap, laces connecting the divided portions of the leg portion, a buckle secured to the flap on one side thereof, and a strap secured to the flap on the other side and adapted to extend beneath the arch portion of the sole to adjustably engage said buckle, whereby the strap and laces will hold the flap in position when the footwear is worn without an overshoe and hold the flap and overshoe in position when an overshoe is worn on the footwear, said article of footwear having the appearance of the usual high top footwear when worn without the overshoe. 30 35 40
